UNITED STATES PATENT OFFICE.

HENRY SCHRECK, OF ST. LOUIS, MISSOURI

FUEL-PUMP.

1,205,669.

Specification of Letters Patent. Patented Nov. 21, 1916.

Application filed May 22, 1915. Serial No. 29,895.

To all whom it may concern:

Be it known that I, HENRY SCHRECK, a subject of the Emperor of Germany, residing at St. Louis, State of Missouri, have invented certain new and useful Improvements in Fuel-Pumps, of which the following is a full, clear, and exact description, reference being had to the accompanying drawings, forming a part hereof.

10 My invention has relation to improvements in fuel-pumps; and it consists in the novel features of construction more fully set forth in the specification and pointed out in the claims.

15 The present invention is primarily directed (though not restricted) to fuel feed-pumps for internal combustion engines and particularly what are known as slow combustion or high pressure internal combustion engines in which liquid fuel is ignited by the high temperature of the compressed air charge present in the cylinder.

20 The object of the invention is to provide a pump, the fuel-feed whereof may be automatically regulated and controlled according to the load imposed on the engine, with a view of maintaining the speed of the engine approximately uniform under variable load conditions. The pump herein is of the 25 reciprocating piston or plunger type, the fuel being drawn into the pump cylinder with a stroke of the plunger in one direction, and expelled from the cylinder with a stroke of said plunger in the opposite direction, the quantity thus expelled being fed to the engine cylinder where it is subsequently ignited in the manner above indicated. The improvement herein is in the main directed to the plunger element of the 30 pump, said plunger forming the complement of a coöperating member to which reciprocation is imparted from some moving part of the engine, preferably the gear or governor shaft, the strokes of said coöperating member being constant, whereas the 35 strokes of the plunger are variable, being automatically and directly affected by the load imposed on the engine, the strokes increasing and decreasing in direct proportion 40 to said load. The independent control over the plunger whereby the stroke thereof is susceptible of variation according to the load imposed on the engine, is made possible 45 under my invention by interposing a yielding connection between said plunger and its

coöperating complementary member (the strokes of which are constant), the controlling element for the plunger being operated by the engine governor or by any movable member responsive to the load conditions.

5 A further object is to provide a feed regulating pump which is susceptible of many modifications without a departure from the underlying principle of the invention; one 60 which is equally applicable to engines of one cylinder or of the multicylinder type; one which is positive and reliable, comparatively simple in construction, and one possessing further and other advantages better apparent from the following detailed description of the invention illustrated in the accompanying drawings in which—

Figure 1 represents an end elevation of an internal combustion engine showing one 75 form of my invention applied thereto; Fig. 2 is a longitudinal middle vertical section of the pump shown in Fig. 1; Fig. 3 is a horizontal section on the zig-zag line 3—3 of Fig. 2; Fig. 4 is a vertical cross-section on the line 4—4 of Fig. 2; Fig. 5 is a vertical section on the order of Fig. 2 showing a modification of my invention; Fig. 6 is an end elevation of Fig. 5; Fig. 7 is an enlarged vertical cross-section on the line 7—7 of Fig. 85 5; Fig. 8 is an enlarged vertical cross-sectional detail on the line 8—8 of Fig. 5; Fig. 9 is a front elevation of a further modification of pump having independently spring-controlled plungers, parts being in section; and Fig. 10 is a combined side elevation and vertical section on the zig-zag line 10—10 of Fig. 9.

Referring to the drawings, and for the present to Figs. 1 to 4 inclusive, E represents the upper portion of a conventional internal combustion engine, and S the gear-shaft carrying the governor G which controls the sliding collar C. P represents the pump body and *a* the oil line leading from the pump to the atomizer, all as well understood in the art. Disposed on the shaft S above the collar C is an eccentric 1 from which leads the eccentric link 2, the opposite end of said link being pivotally coupled by means of a pin *a* to a piston head 3 operating in a bearing or cylinder 4 of the pump body, the piston head being provided with an intermediate reduced portion 3' from which in turn leads the still further reduced 110

portion or stem 3", an annular shoulder s being formed between the members 3', 3". The stem 3" operates loosely through one of the end walls of a reciprocating sleeve 5 or housing 5 suitably mounted and guided in the pump body, the inner end of the stem terminating within the housing and being provided with a reduced screw terminal 6 carrying a nut n which secures to the stem a disk or washer 7 bearing against the end of the stem, said disk forming an abutment for the adjacent end of an expansion spring 8 coiled about the stem and interposed between the disk and the terminal wall of the housing traversed by said stem. The opposite end wall of the housing is provided with laterally projecting ledges 9 for a purpose presently to appear, said ledges and wall forming in effect a terminal cross-piece to which the plungers 10 are secured in any suitable mechanical manner. It may be stated in passing that the spring 8 normally tends to force or drive the sleeve or spring housing 8 against the shoulder s of the piston section 3', permitting the piston head 3 and the housing 5 under certain conditions (to be hereinafter specifically referred to) to reciprocate as a unit under the driving action of the eccentric 1. The connection 20 between the stem 3" and the sleeve or housing 5 is a telescopic one, the member 5 being susceptible of control independently of the reciprocations of the piston head 3, the strokes of which are constant because of its connection with the gear-shaft S through the eccentric 1. The several plungers 10 (where more than one plunger are used, as would be the case with a multicylinder engine), operate through suitable stuffing boxes 11 on the pump body, the plungers reciprocating in passage-ways 12 which in effect constitute cylinders for the plungers, said pump cylinders or passage-ways communicating each with a port ϕ leading to a chamber 13 which communicates on the one hand with a fuel collecting or distributing chamber 14 to which the fuel is initially delivered by the feed-pipe 15 leading from any suitable source of fuel or oil supply (not shown) and on the other hand with a valve-easing 16, each chamber 13 being controlled by a check valve V, interposed between it and the chamber 14, and each casting 16 being provided with a check valve V', the oil line ω leading from the valve-easing 16 to its respective engine cylinder, or more particularly, to the atomizer or spray nozzle of such cylinder. The valve V is normally seated by a spring 17, and the valve V' by a spring 18, the valve V unseating with a suction or intake stroke of the plunger 10 to admit liquid fuel into the pump cylinder 12, and seating with an expulsion or discharge stroke, and the valve V' unseating with the 65 expulsion stroke, but closing with the intake or suction stroke of the plunger. These are matters well understood in the art and no claim therefor is made herein, it being within the purview of the skilled mechanic to substitute some other system of check valves should he deem it desirable or necessary.

Pivoted on opposite sides of the pump body P at the ends of suitable arms or brackets 19, directed toward the gear shaft S, are bent levers 20 whose short arms are pivotally coupled to the sliding collar C, the end of the long arm of each lever being pivotally secured to the adjacent end of a link 21 whose opposite end pivotally connects with the outer end of an oscillating arm 22 leading from the adjacent terminal of a rock-shaft or rocker spindle 23 carried by an arm or bracket 24 leading from the pump body, the inner terminals of the rock-shafts being provided with suitable cams 25 (or their equivalent) adapted to engage the adjacent faces of the ledges 9, the cams or their equivalents operating conjointly as quite obvious from the drawing.

The operation of the pump is substantially as follows: Rotation of the shaft S necessarily imparts reciprocation to the piston head 3, and the members 3', 3"; and so long as the housing 5 to which the plungers 10 are secured is unrestrained it will reciprocate conjointly and coextensively with, the member 3, being held to said member by the spring 8 which holds the housing against the shoulder s of the intermediate section 3'. Assume however that the load on the engine lightens so as to increase the speed of the shaft S. The collar C will rise and oscillate the levers 20 to the dotted position indicated in Fig. 2, the levers in turn altering the positions of the parts 21, 22, as indicated, and rocking or rotating the cams 25 in a direction to bear against the ledges 9 and thus intercept or arrest the housing or sleeve 5 before the latter can complete its full intake or suction stroke (with the member 3'). The consequence is that the suction stroke of the housing 5 and hence the suction strokes of the plungers 10 (where there are more than one plunger) will be shorter than the corresponding stroke of the piston head 3 (and the parts 3', 3"), the strokes of which are constant because of its connection with the shaft S through the eccentric 1, the housing 5 lagging behind the member 3' and becoming separated from the shoulder s (on said suction stroke) the spring 8 being correspondingly compressed. The amount of lag will depend on the point of arrest of the ledges 9 by the cams 25, a point determined by the speed of the engine and on the distance to which the collar C has been shifted under such speed. In Figs. 2 and 3 the dotted positions of the housing 5 and the plungers 10 indicate the points of

arrest of these members on the suction stroke, this stroke having been reduced below what would otherwise be a full stroke, so that the quantity of fuel drawn into the pump cylinder 12 with such intake stroke is correspondingly decreased. The intake stroke of the plunger being thus shortened or reduced, it follows that the expelling stroke will likewise be correspondingly reduced, the quantity of fuel expelled by the plungers and delivered to their respective engines being thus decreased, thereby resulting in the lowering of the speed of the engine with a reduction of the load. As the load increases the reverse of these operations takes place; that is to say the point of arrest of the plungers is at such position as to allow the strokes of the plungers to lengthen thereby drawing in more fuel and delivering more to the engine so that the speed of the engine may increase. It follows therefore that with any decrease in the load imposed on the engine (which tends to increase the speed of the engine) a decreased amount of fuel is delivered to the engine cylinder, and with any increase in the load (which tends to decrease the speed) an increased quantity of fuel is delivered to the engine, the result being that the speed of the engine is maintained approximately uniform. In the present embodiment of my invention the arrest of the housing 5 and its plungers 10 takes place on the intake or suction stroke (the expelling stroke necessarily being correspondingly shortened) but the same result can be accomplished by effecting the arrest on the expelling or discharge stroke of the plunger without departing from the spirit of my invention. In other words I do not wish to be restricted to any specific manner of bringing about a variable stroke of the plungers under variable load conditions.

The construction by which the arrest of the stroke of the plunger (or plungers) is effected is of course susceptible of considerable modification. In Figs. 5 to 8 inclusive I illustrate a modification where a wedge is availed of to effect the arrest referred to. Referring to said figures, the inner arms of the levers 20' have depending pivotally therefrom the links 26 which are in turn pivotally secured to the arms 27 of a ring 28 mounted slidably on a stem 29 between the adjacent ends of the coiled expansion springs 30, bearing with their opposite ends against the tension adjusting nuts 31, passed over the stem, the upper end of the latter terminating in a fork or U-shaped bracket 32 between whose members is pivotally secured the end of one arm of a vertically oscillating bell-crank 33, the forked terminal of the opposite arm having pivotally coupled thereto the adjacent end of a link 34 whose opposite end is pivotally secured to a wedge 35 suitably guided in the pump frame or body P', the inclined face of the wedge being engaged by a roller 36 at the terminal of one of the arms of a double bell-crank lever 37 pivoted about a spindle or shaft 38 on the pump frame. The vertical arm of said double bell-crank lever operates with its free rounded end in a loop or strap 39 projecting from the adjacent head of the housing 5, said loop operating in a chamber N formed in the frame P' 70 behind the cap-plate 40 carrying the plunger bearing 41. Operating in the bearing 41 is a stem 42 projecting from the plunger head 43 to which the several plungers 44 are secured. These latter operate in their respective pump cylinders (not shown) in the cylinder member P" to which leads the supply pipe 15' and from which lead the oil lines 16' as well understood in the art. The head 43 is provided with a chamber or opening O in which freely operates the rounded terminal of the third arm of the double bell-crank lever 37, the walls of said chamber or opening being suitably contoured to allow for free vertical oscillation of said bell-crank arm. The springs 30, 30, are sufficiently stiff to cause the stem 29 to be moved up and down under normal working conditions with any oscillations of the levers 20' as a result of any shifting of the collar C, the stem in turn imparting the necessary oscillations to the bell crank 33 to cause the latter to move or reciprocate the wedge 35. The wedge in its movements in turn oscillates the bell crank 37 which controls the strokes of the housing 5', and since this housing is in turn connected to the head 43 through the bell-crank 37, it follows that said head and the pump plungers leading therefrom will have their strokes directly affected by said member 5', the same as in the first construction described. Should the wedge 35 for any reason fail to respond to the oscillations of the levers 20', the springs 30 will yield to the levers so that no damage will result to the machinery. The springs 30 thus constitute a safety connection between the levers 20' and the bell-crank 33. Features shown in Figs. 5, 6, 7, but not alluded to are substantially the same as in the first form described and are accordingly identified by the same reference numerals and symbols.

In the forms thus far described a single spring 8 controls the several plungers; but it is apparent that I may provide each plunger with an independent spring control. Such an arrangement is shown in Figs. 9 and 10. In this modification the gear shaft (not shown) is supposed to be horizontal, the pump plungers 50 operating each through a chamber h of a head 51 coupled by means of a yoke or strap 52 to the piston head 53, the plunger being provided within the chamber with a collar or shoul-

der 54 serving as an abutment for one end of an expansion spring 55 whose opposite end bears against the hollow screw plug 56 through which the plunger operates, said 5 plug closing the outer end of the chamber. In this modification the eccentrics 57 (or their equivalents) are distributed along a rock-shaft 58 (on the order of the rock-shaft 23 described in connection with the 10 first form) terminating in lever arms 59, which are controlled by levers (not shown) pivoted to the arms 60, the levers being connected to the collar C or its equivalent as in the first form described. It will be seen 15 from the connections described that a rotation of the eccentrics 57 in proper direction will force down the plungers 50, that is to say, cause their arrest at a given point of their upstroke while the member 51 is allowed to make its full stroke with the piston 53. When the eccentrics 57 do not assert themselves, the plungers 50 being held to the head 51 by the resilient action of the 20 springs 55, will make a full stroke with said head; otherwise the plunger strokes will be arrested at points determined by the degree 25 of rotation imparted to the eccentrics under variable load conditions, and hence said strokes will become variable. In this modification 30 2' represents the eccentric link leading from the gear shaft (not shown), P'' the pump cylinder-member, and x'' the oil line.

The means whereby the strokes of the 35 plungers of the pump may be regulated to conform to the load imposed on the engine, and whereby the quantity of fuel delivered to the engine may be proportioned to said load so as to maintain an approximately 40 uniform speed under all conditions, may be modified still further, but the examples here shown are sufficient to indicate that my invention is susceptible of many variations in details without involving a departure from 45 either the spirit or nature of the invention. The member 5 (with its plungers 10) may be considered as the complement of the member 3 (and its extensions 3', 3''), reciprocating jointly and coextensively, there- 50 with under normal conditions or conditions under which the full capacity of the pump cylinder 12 is availed of, the strokes of the member 5 being in addition susceptible of variation and control by the members 20 or 55 any equivalent thereof responding to load conditions (through the governor) the telescopic connection as herein shown, between the members 3'' and 5 being the most feasible for the purpose in view. 60 Details of construction here shown, but not alluded to are either well understood in the art or fall within the purview of the skilled mechanic, and a description thereof is unnecessary in the present connection.

Having described my invention what I 65 claim is:

1. In combination with the gear-shaft of an internal combustion engine, a speed governor on said shaft, a source of liquid fuel supply, a feed pump provided with a cylinder having a reciprocating plunger therein, a complementary member yieldingly and telescopically connected to the plunger, means interposed between the gear-shaft and said complementary member for imparting 75 to the latter reciprocations of constant stroke, and means controlled by the governor for controlling the intake stroke of the plunger whereby the quantity of fuel fed to the engine is regulated to suit the load 80 conditions imposed on the engine.

2. In combination with the gear-shaft of an internal combustion engine, a speed governor on said shaft, a reciprocating member operating under constant stroke and actuated from the gear-shaft, a member telescoping with, and movable longitudinally along the reciprocating member, the latter being provided with a shoulder for limiting the movement of the telescoping member in one direction, an abutment on said reciprocating member, a spring interposed between said abutment and the telescoping member for normally forcing the latter against the shoulder of the reciprocating member, feed-pump plungers carried by the telescoping member, an oscillating member actuated by the speed governor, and suitable devices interposed between the telescoping member and oscillating member aforesaid, for forcing the telescoping member away from the shoulder of the reciprocating member against the tension of the spring aforesaid, with any response of the governor to the load conditions imposed on the engine, whereby the 100 strokes of the telescoping member and of the plungers carried thereby may be varied according to said conditions independently of the constant strokes of the reciprocating member.

3. In combination with a gear-shaft of an internal combustion engine, a speed governor on said shaft, a piston head, an eccentric on the shaft, an eccentric-rod, or link connecting said piston head to the eccentric for imparting reciprocations to the piston, a stem leading from the piston, an offset or shoulder being formed at the base of the stem, a sleeve loosely receiving the stem and adapted to be arrested by said shoulder, an expansion spring coiled about the stem and interposed between a terminal wall of the sleeve and a fixed abutment on the stem and tending to drive the sleeve against the shoulder aforesaid, a cross-piece at the outer end of the sleeve projecting beyond the peripheral walls of the sleeve and forming suitable ledges, cams engaging

the inner faces of the ledges, feed-pump plungers carried by the cross-piece along the outer face thereof, a pair of oscillating bent levers pivoted at intermediate points of their 5 lengths, one arm of a lever being actuated by the governor, and intermediate connections between the opposite arm of the lever and its corresponding cam for actuating the

latter and regulating the stroke of the sleeve and the plungers. 10

In testimony whereof I affix my signature, in presence of two witnesses.

HENRY SCHRECK.

Witnesses:
